UNITED STATES PATENT OFFICE.

EMERSON B. MOSELEY, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

HINGE FOR FILING APPLIANCES.

1,148,918.

Specification of Letters Patent.

Patented Aug. 3, 1915.

Original application filed June 20, 1911, Serial No. 634,268. Divided and this application filed October 30, 1911, Serial No. 657,586. Renewed December 31, 1914. Serial No. 879,961.

To all whom it may concern:

Be it known that I, EMERSON B. MOSELEY, a citizen of the United States, residing at Alliance, in the county of Stark and State 5 of Ohio, have invented a certain new and useful Hinge for Filing Appliances, the same being illustrated and described, but not claimed, in my application for Letters Patent filed June 20, 1911, Serial No. 634,268, 10 of which application this is a divisional part, and of which invention the following is a specification.

The invention relates to an appliance specially adapted for filling bills of sales or 15 accounts, as of a retail merchant, and more particularly to that class of appliances containing a series of frames or leaves normally located uprightly face to face, in a rectangular pack, the frames being hinged 20 or jointed together at the lower ends, so that they can be rotated forward to a prone position, face to face, in a rectangular pack, which rotation exposes and gives access to the faces of the several frames.

25 The object of the invention is to provide a hinged connection between the jointed ends of the frames, which will permit these ends to slightly separate when necessary to accommodate a greater number of bills than 30 can be filed in the normal interval between the frames; and, in the present embodiment, this object is attained by providing a hinge having an intervening link-plate pivoted below to the edge of one frame and above 35 to the face of the adjoining frame, so that the leaves may separate by the swinging of the intervening link-plate on its pivots. Coupled with the expansible joint, thus formed, may be provided one or more expansion springs extending through apertures in the lower ends of the frames to normally hold the same closed together.

The present embodiment of the invention, thus set forth in general terms, is illustrated 45 in the accompanying drawing, forming part hereof, in which—

Figure 1 is a lower end view of a pack of frames, showing the jointed ends of the several frames in their normal closed-together 50 relation; Fig. 2, a sectional view of the pack of frames in upright position, showing

bunches of bills therein and the hinged ends expanded apart; and Fig. 3, a fragmentary sectional view of the hinged joint between two of the frames.

55

Similar numerals refer to similar parts throughout the drawing.

The frames 1, 2 and 3 are preferably made of metal sheets or plates, with the reinforcing side and end strips 4 and 4^a secured on 60 their faces, which strips serve to stiffen as well as to separate the frame plates, and also constitute a rim within which are formed the recesses 5 in the faces of the frames for receiving the bunches of bills 5^a 65 to be filed in the appliance, which are preferably retained by means of the spring clips 6.

Each hinge between the lower ends of the frames of the pack is composed of the pivot- 70 plates 7 and 7^a with the intervening link-plate 8, and the parts are so connected and arranged that the pivot 9 of the plate 7 is located at the edge of the lower end of one frame, and the pivot 9^a of the plate 7^a is 75 located in the face of the adjoining frame at a substantial distance above the lower edge thereof; and a suitable recess, as 10, is preferably provided in the face of one frame to receive the link-plate, so that the frames 80 can be folded closely together.

By this construction and arrangement, it is evident that the jointed ends of the frames may be slightly separated by a swinging of the link-plate upon its pivots, as shown in 85 Figs. 2 and 3, the endwise movement of the frames with respect to each other, caused by this swinging, being so slight as to be negligible; and that the frames will thus accommodate themselves to a thicker pack- 90 of bills than could be filed in the recesses of the frames when the reinforcing side and end strips thereof are in contact with each other.

The joint springs 11 may be provided for 95 normally holding the hinged ends of the frames together, and, when used, these springs are preferably in the form of expansion springs, as shown, located in suitable apertures 12 provided in the lower end 100 portions of the frames; and the ends of these springs are secured to the foremost

and rearmost frames, so that the tension of the springs acts to draw the hinged ends of the frames together, it being evident that the flexibility of these springs permits the frames to be rotated on their hinged joints.

5 I claim:

1. A series of frames, joints connecting adjoining frames together along one edge and permitting an oscillation of the frames relative to each other and a bodily separation of two adjacent frames from each other, and means arranged to be placed under tension when said frames are operated.
- 10 2. A series of frames normally located face to face in a rectangular pack, a hinged connection between corresponding ends of the frames including a link plate pivoted at one end to the edge of one frame and at the other end in the face of the adjoining frame at an interval from the corresponding edge thereof, whereby the hinged ends of the frames may be separated by a rotation of the link plate on its pivots, and means connected to the opposite end frames of the series of frames arranged to put under tension when one or more of said frames are separated.
- 15 25

3. A series of frames normally located face to face in a rectangular pack, and a hinged connection between corresponding ends of the frames including a link plate pivoted at one end to the edge of one frame and at the other end in the face of the adjoining frame at an interval from the corresponding edge thereof, and a laterally flexible expansion spring normally holding the jointed ends of the frames together, whereby the hinged ends of the frames may be separated by a rotation of the link plate on its pivots.

30 35 40 45 50

4. A series of frames, devices connecting said frames together along one edge and permitting said frames to swing relative to each other and to separate bodily one relative to the other, and means, fixed to the opposite end frames of the series and extending through each of the intermediate frames, arranged to be placed under tension when one or more of said frames are separated from the adjacent frame or frames.

EMERSON B. MOSELEY.
